METHOD OF MAKING WIRE ROPE

Richard Duane Green and William E. Craig,
Trenton, N. J., assignors to John A. Roebling's
Sons Company, Trenton, N. J., a corporation
of New Jersey

Application October 12, 1932, Serial No. 637,442

8 Claims. (Cl. 117—16)

This invention relates to the manufacture of wire rope, its object being to provide a novel method of making such rope.

In the manufacture of wire rope in the so called planetary machine, the wire supply spools are given a reverse rotation relatively to the rotating flier or frame carrying the spools so as to avoid or control the torsion in the wires resulting from a revolution of the bobbins with the flier, and such reverse rotation of the spools has been arranged in some cases so that a small amount of twist is secured in the wires, which may be in the same direction as the helices are laid up or opposed to them, that is, over-twist or under-twist, this being found of advantage in certain kinds of wire rope. Such planetary machines, however, necessarily operate at a comparatively slow speed because of the large diameter and heavy weight of the rotating flier carrying the spools, and there are other serious objections to this type of machine in producing over-twists or under-twists.

In accordance with the present invention, we twist the wires on their axes in the spooling machine or otherwise before passing them into the laying up machine, so that locked spools or floating spool cradles may be used in the laying up machine, and we thus secure important advantages in the manufacture of the rope.

The twist is preferably put into the individual wires in winding the wire on the spools, and this may be done in a spooling machine separate from the laying up machine, or the laying up machine may be provided with a twisting mechanism separate from and in advance of the laying up mechanism, and the twisted wires led direct from such twisting mechanism to the laying up machine, the twists in the wires being maintained from such twisting mechanism to the rope closing point.

If the twists are put in the wires in a spooling machine separate from the laying up machine, and the spools then transferred to the laying up machine, the end of the wire will be secured to the spool before winding up and the outer end of the wire after spooling, so as to hold the twists put into the wires and the wire from the supply spools will be threaded into the laying up machine with the twist thereon and secured at the rope closing point. A convenient way to maintain the twist in threading up is to clip the wire to prevent untwisting or to twist the wire further for a short length so as to compensate for any untwisting in threading up so as to maintain these twists up to the closing point.

The accompanying drawing shows a simple machine which may be used for twisting the wires. In the drawing:

Figure 1 is a diagrammatic side elevation of the machine; and

Figure 2 is a similar sectional plan view of the distributor and winding-up spool.

A is the rotating flier in which wire spool B is mounted to rotate for unwinding the wire, the flier A being driven by the pulley 10. C is a pull-off 10 of common type mounted in the frame D. E is a distributor mounted in frame F, and G a winding-up spool mounted in frame H. The wire x passes from spool B through the central passage in rotating flier A and is twisted by the rotation of 15 the flier as drawn off by the pull-off C, over which it passes, through the distributor E, where it is traversed for layers on the spool G, this traverse being secured by guide 11 traversed to and fro by the rotating shaft 12 with the double helix, 20 as usual in such distributors. The advance and outer ends of the wire may be secured to the spool G to prevent untwisting in any suitable manner, and as shown, are passed respectively through openings 1, 2 in the side flanges of the 25 spool G and tied around the flange. Any desired twist or number of twists may be secured, this depending upon the rotative speed of flier A relatively to the rate of pull off.

With the twist thus put into the wires independently of the laying up machine, the wires may be used in any common or suitable type of laying up machine, for instance, in the common planetary machine, and the bobbins may be locked so as to change the twist previously put into the 35 wires or may be run with a rotation reverse to the flier so as to modify the previous twist, or to maintain the previous twist, but an important advantage of the invention is that the previously 40 twisted wires may be used in the common horizontal machine with floating spool cradles mounted axially to the flier or rotating spool carrying frame, in which case the twist put in previously will not be changed, or may be used in any machine in which the rope is rotated for laying up 45 the wires, and in the latter type of machine either with reverse rotation of the bobbins to vary the twists previously put into the wires or otherwise. The single core wire used in metal core rope also 50 may have a suitable twist put into it by supplying the twist independently of the laying up machine or may be used without twist as usual.

The invention may be used and is of particular value in making rope formed of individual wires laid up helically and a plurality of such rope 55

strand may then be laid up helically to form a rope, or the invention may be used in twisting strands previous to their use in the laying up machine. As the twist may be made of any amount desired, it has been found possible to twist the wires in a direction opposed to the laying up helix to such an extent as to prevent the crankiness or tendency to coiling or kinking of ordinary rope and even offset the tendency of the wires or strands to uncoil and spread out at a cut end or birdcage, and thus make a so called dead lay rope without preforming to permanent helices.

Many important advantages in rope manufacture are secured by the invention, including among others, the following:

A great increase in speed of manufacture, and consequent decrease in cost is possible as compared with the planetary machine. The common horizontal machine with the spools in axially mounted floating cradles may be run much more rapidly because of the comparatively small diameter and less weight of the rotating flier or frame, but it is impossible to put in the desired 25 over- and under-twists with the floating cradles. By putting the desired twist into the wires in the spooling machine, or otherwise independently of the laying up machine, the rope with any desired twists may be made in such a horizontal 30 machine with consequent great increase in the speed of manufacture. The importance of this is evident from the fact that such horizontal machines usually are run about 600 R. P. M. and the planetary machines about 100 R. P. M. 35 A more uniform twist for the wires is secured than by the planetary machine with over-twist or under-twist because of the shorter length of wire handled in twisting, thus providing better control of the wires. Moreover, in planetary 40 rope manufacture with two or more tiers of spools the difference in length of wire from the different spools to the closing point makes it difficult if not impossible to secure uniform over- or under-twists in the wires. These difficulties 45 in the planetary machines with a long run of wire are increased, also, by the friction of the wire guides which are necessary between the spools and closing point, thus affecting the twists, and the same is true as to the horizontal machines. This friction may readily be compensated for by the previous twists of the present 50 invention. Moreover, the twist in the wires tends to prevent the effect of the friction accumulating in a section of the rope, and a more uniform product is obtained.

Spooling machines or other mechanism for twisting the wires independently of the laying up machine can readily be adjusted to vary the twists as desired, while in securing widely varied over-twists or under-twists in planetary machines, it is practically necessary to design the machine for a certain range of over-twist or under-twist, it being found in practice that a mechanism adjustable for widely varied twist 65 is not satisfactory and it usually is employed only for experimental purposes. The center wire or core wire may be twisted as well as the outer wires, and it is possible to use twists on one wire or any number of wires in a rope as is desired, this enabling the production of rope of widely varying characteristics.

In making lang lay rope, the twists of the wires in the strands may readily be in either direction and in any amount desired, so that exactly the effect desired in the lang lay rope may

be secured, and such lang lay rope may be made with the desired twists in a horizontal machine with floating spool cradles or in any other machine arranged for avoiding torsion.

In making lang lay rope, also, it is possible to produce a tighter rope than with the methods now in use. Attempts have been made to tighten the lang lay rope in closing, but these have not been satisfactory. With the present invention the twists in the wires may be made such as to 10 tighten the lang lay rope to any extent desired.

The twists may be calculated so as to allow for the tendency to crankiness in the usual standard wire rope and avoid this crankiness so that the rope will lie straight without coiling or kinking 15 on itself, and, as stated above, it is possible to make dead lay rope without preforming, by making the twist such as to compensate for the tendency of the wires to spread at the end or birdcage.

The term rope used herein is intended as a 20 broad term including rope or rope strand made by laying up helically a number of individual wires, and rope made by laying up helically a number of strands made of individual wires, and the term wire is used to include both single wires 25 and strands formed of a plurality of wires, unless otherwise specified.

What is claimed is:

1. The method of making wire rope, which consists in twisting some or all of the rope wires on 30 their axes, then transferring the twisted wires to the laying up machine while maintaining the twists, and laying up the rope wires helically to form the rope.

2. The method of making rope having a wire 35 core, which consists in twisting the core wire and some or all of the outer wires on their axes, then transferring the twisted core wire and outer wires to the laying up machine while maintaining the twists and laying up the outer wires on 40 the core wire to form the rope.

3. The method of making wire rope, which consists in twisting some or all of the rope wires on 45 their axes, winding the wires on spools and maintaining the twist, transferring the spools to the laying up machine, threading the wires to the closing point and maintaining the twists, and laying up the rope wires helically to form the rope.

4. The method of making wire rope, which consists in twisting some or all of the outer rope 50 wires and a core wire on their axes, winding the wires on spools and maintaining the twists, transferring the spools to the laying up machine, threading the wires to the closing point and maintaining the twists, and laying up the outer 55 wires helically on the core wire to form the rope.

5. The method of making wire rope of individual wires, which consists in twisting some or all of the individual wires on their axes, then transferring the twisted wires to the laying up machine, and laying up the rope wires helically to 60 form the rope.

6. The method of making wire rope of individual wires, which consists in twisting some or all of the individual wires on their axes, winding the 65 wires on spools and maintaining the twist, transferring the spools to the laying up machine, threading the wires to the closing point and maintaining the twists, and laying up the rope wires helically to form the rope.

7. The method of making wire rope formed of strands of a plurality of individual wires, which consists in twisting some or all of the individual 75 strand wires on their axes, then transferring the twisted wires to the laying up machine and lay-

ing up the wires helically to form the strand, and then laying up the strands helically to form the rope.

8. The method of making wire rope, which
5 consists in twisting some or all of the wires on
their axes before submitting them to the laying
up motion, then transferring the wires to the

mechanism producing the laying up motion and
producing the laying up motion by a relative mo-
tion of revolution between the twisted wires and
the finished rope to lay up the wires helically to
form the rope.
